[57] CLAIM

The ornamental design for a shower head, as shown and described.

DESCRIPTION

FIG. 1 is a side elevational view of a shower head embodying our new design, the opposite side being a mirror image of the side shown;

FIG. 2 is a side elevational view taken ninety degrees to the right of the side shown in FIG. 1;

FIG. 3 is a top plan view thereof;

FIG. 4 is a bottom plan view thereof; and

FIG. 5 is a side elevational view similar to FIG. 1, but showing the spray control handle in a different position.

FIG. 3

FIG. 1

FIG. 2

FIG. 4

FIG. 5
